J. F. SAUERMAN,
EARTH BORING MACHINE,
APPLICATION FILED JUNE 8, 1917.

1,241,665.

Patented Oct. 2, 1917.

UNITED STATES PATENT OFFICE.

JOHN F. SAUERMAN, OF LITTLE ROCK, ARKANSAS, ASSIGNOR OF FORTY-EIGHT ONE-HUNDREDTHS TO BEN D. SCHAAD, OF LITTLE ROCK, ARKANSAS.

EARTH-BORING MACHINE.

1,241,665.

Specification of Letters Patent.

Patented Oct. 2, 1917.

Application filed June 8, 1917. Serial No. 173,454.

To all whom it may concern:

Be it known that I, JOHN F. SAUERMAN, a citizen of the United States, residing at Little Rock, in the county of Pulaski and State of Arkansas, have invented a new and useful Improvement in Earth-Boring Machines, of which the following is a specification.

This invention relates to earth boring machines especially designed for digging post holes, and has for its object to provide an improved light portable machine of this kind in which the boring tool may be rotated by motor and moved axially by hand, whereby the feeding of said tool down into the earth may be easily regulated according to the hardness of the strata through which it is passing, and the danger of choking or injuring the tool is avoided.

Another object is to provide for taking up slack in the hand operated means for moving the tool axially, and a further object is to automatically lock said means against reverse movement while the tool is being fed into the ground.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a broken front elevation of a boring machine constructed substantially in accordance with this invention, the sprocket chain for moving the tool axially being omitted.

Fig. 2 is a broken side elevation of the machine.

Fig. 3 is a section on the line III—III of Fig. 1, showing the squared tool feeding rod engaging a similarly shaped passage through the horizontal gear.

Fig. 4 is a section on the line IV—IV of Fig. 1, drawn to a larger scale, and

Fig. 5 is a detailed rear face view of the cross head and guide track therefor, also drawn to a larger scale.

The boring mechanism is mounted on a pair of parallel beams 1 supported on axles 2 carrying wheels 3, and constituting a light portable truck on which said mechanism

may be readily moved about. At one end of the truck a transverse frame 4 is fastened to the beams 1 and provided with a vertical journal bearing in which is fitted the hub 5 of a horizontal bevel gear 6. Said hub projects below the journal bearing and is fitted with a collar 7 secured by a bolt 8 for retaining the hub and gear in proper position.

The frame 4 is further provided with a horizontal journal bearing for a shaft 10 carrying a bevel pinion 9 and pulley 11. The pinion 9 meshes with the gear 6, and the pulley 11 is connected by a belt 12 with any suitable motor conventionally indicated at 13, Fig. 2. The gear 6 and hub 5 have an angular, preferably square, passage extending centrally and vertically therethrough, and in this passage is fitted to slide a rod 14 angular or square in cross section and having a socket 15 at its lower end in which a boring tool 17 may be detachably fastened by a clamping bolt 16. From the foregoing it will be seen that the boring tool 17, rod 14 and gear 6 may be rotated by the motor 13 through the belt 12, pulley 11, shaft 10 and pinion 9.

The upper end of the rod 14 is rounded, as at 18, and said rounded portion is fitted to turn in a cross-head consisting of a metal central portion 19 and wooden end portions 20, best shown in Fig. 4. The wooden end portions of the cross-head are adapted to slide in vertical parallel angular guide rails 21 which may be made of a single piece of channel iron bent at the middle and having its ends suitably fastened to the top of the frame 4, as illustrated in Fig. 1. Collars 22 and 23, respectively, are placed on the round portion 18 of the rod 14 below and above the cross-head, and they and the cross-head are held in position by a lock nut 24 on the upper extremity of the rod.

To manually move the rod 14 axially in its bearing in the gear 6 and hub 5, a shaft 25 is journaled horizontally in bearings 26 on the frame 4 and provided with a hand crank 27 at one end and a sprocket wheel 28 at an intermediate point in line with the rod 14. A sprocket chain 29, Fig. 2 is passed around said sprocket wheel 28 and has one end fastened to the cross-head 19 by a bolt 30. The other end of the sprocket chain is passed over a sheave 31, mounted between the upper ends of the guide rails 21 above the cross-head, and attached to a hook 33 on 110

a plate 32 vertically adjustable on said cross-head, to take up slack in said chain, by means of a slot 34 and bolt 35, Fig. 5.

The shaft 25 also carries a ratchet wheel 38 which may be engaged by a gravity pawl 37 pivoted between ears or lugs 36 on the frame 4 for retaining the rod 14 and tool 17 in elevated position and preventing the feeding thereof into the ground. When it is desired to feed said rod and tool downwardly, as during the boring operation, the pawl 37 may be swung back away from the ratchet wheel, as will be readily understood.

Having thus described my invention, what I claim as new and desire to secure by Letters Patent of the United States is:

1. In an earth boring machine, the combination with a rotatable and axially movable boring tool, of means for rotating said tool, a cross-head operatively connected to said tool, guide rails for the cross-head, means for moving the tool axially including a sprocket wheel and chain, and a sheave supported by said guide rails above the cross head, said chain being fastened at its ends to the cross-head and having one end portion passed over said sheave.

2. In an earth boring machine, the combination with a rotatable and axially movable boring tool, of means for rotating said tool, a cross-head operatively connected to the tool, guide rails for the cross-head, a sheave supported by said guide rails above the cross-head, a rotatable sprocket wheel, a sprocket chain engaging said sprocket wheel and passed over said sheave, the ends of said chain being fastened to said cross-head, and a plate adjustable on the cross-head,

and connected to one end of the sprocket chain, whereby slack may be taken up in 40 said chain.

3. In an earth boring machine, the combination with a rotatable and axially movable boring tool, of means for rotating said tool, a cross-head operatively connected to 45 the tool, means for guiding the cross-head, a sheave supported by said guiding means above the cross-head, a rotatable sprocket wheel, a sprocket chain engaging said wheel and passed over said sheave, the ends 50 of said chain being fastened to said cross-head, a plate adjustable on the cross-head, and a hook on said plate adapted to engage any one of the links of one end portion of the sprocket chain for the purpose specified. 55

4. In an earth boring machine, the combination with a supporting frame, of a gear journaled therein and having an angular passage therethrough, a rod angular in cross section fitted in said passage in the 60 gear, means for rotating the gear, a cross head operatively connected to the tool, means for guiding the cross-head, a sheave supported by said guiding means above the cross head, a shaft also journaled in the 65 frame, means for rotating said shaft, a sprocket wheel on said shaft, a sprocket chain engaging said sprocket wheel and passed over said sheave, the ends of said chain being connected to the rod for moving 70 the same axially, a ratchet wheel also mounted on said shaft, and a pivoted pawl normally held by gravity in engagement with said ratchet wheel for the purpose specified.

JOHN F. SAUERMAN.
